UNITED STATES PATENT OFFICE

2,662,634

AUXILIARY CONVEYER EXTENSION

Hubert A. Tintes, West Fargo, N. Dak.

Application October 16, 1950, Serial No. 190,273

2 Claims. (Cl. 198—93)

1

This invention relates to an auxiliary conveyor attachment, adapted to be mounted on a conventional elevator conveyor to deliver material thereto.

It is a definite problem in the handling of granular products such as small grains and the like to feed said material to the conventional elevator conveyor units. The grain is often stored in large bins, from which a large portion must be shoveled in order to completely empty the bin. 10

It is an object of my invention to provide an auxiliary conveyor attachment, adapted to be mounted for vertical and horizontal swinging movement at the material receiving end of a conventional elevator conveyor for delivery of 15 material from a relatively inaccessible remote point to the elevator conveyor unit.

It is another object to provide an auxiliary conveyor attachment adapted to be connected to a conventional elevator conveyor and to extend a 20 substantial distance horizontally outwardly from the lower material receiving end of said conveyor.

It is still another object to provide an auxiliary conveyor attachment or extension for connection 25 with an elevator conveyor and constructed in the form of an auger adapted to be driven from a source of rotary power to deliver material to the elevator conveyor, and having a removable hopper unit surrounding a portion of said auger to 30 permit said auger to be used as a drag-out conveyor as well as to receive the flow of material through a restricted outlet into the hopper.

It is a further object to provide an auxiliary conveyor attachment provided with a removable 35 mounting connection for securing the delivery end of the auxiliary conveyor to discharge material into the elevator conveyor and having an upright mounting pin as well as a substantially horizontal mounting pin to permit swinging 40 movement on a vertical as well as a horizontal axis.

These and other objects and advantages of my invention will more fully appear from the following description made in connection with the accompanying drawings wherein like reference characters refer to the same or similar parts throughout the several views, and in which:

Fig. 1 is a top plan view of my conveyor attachment, as horizontally mounted on a conventional elevator conveyor, and showing the outline of the removable hopper in dotted lines and showing the attachment in horizontally swung position in dotted lines.

Fig. 2 is a side elevational view of my attachment with the hopper assembled thereon, and showing said attachment in inclined relation.

Fig. 3 is a transverse sectional view taken substantially along the line 3—3 of Fig. 2.

Fig. 4 is an exploded perspective view showing 50

2

the connector mounting for the auger extension; and

Fig. 5 is an exploded view showing the parts of the hopper as removed from the auger extension.

As illustrated in the accompanying drawings, I provide an extension conveyor consisting in an auger 7 fixed to a rotary shaft 8 which is journaled in suitable bearings respectively mounted in end plates 9 and 10. As best shown in Fig. 5, the forward portion of the auger 7 is enclosed in a casing 11 and a pair of opposed hopper mounting members 12 and 13 are fixed at their forward ends to the rear portion of casing 11 and are mounted at their rear ends on the end plate 10.

A hopper designated as an entirety by the letter A is removably mounted on the mounting members 12 and 13. A bottom closure casing 14 is slidably mounted on the flanges along the lower edge of each of the mounting members 12 and 13 to enclose the bottom of the auger 7. A pair of end closure plates 15 and 16 are respectively connected at the forward and rear ends of the hopper. The end plate 16 may be removably secured to end plate 10 as by suitable screws and the forward end plate 15 merely rests on the top of the casing 11. A pair of side plates 17 interconnect the two end plates 15 and 16 and hold the forward plate 15 against shifting movement. A divider and distributing member 18 having an inverted V-shaped cross-sectional contour is interposed between said end plates 15 and 16, and is secured thereto by the brackets 19. It should be noted that the upper portion of the hopper can be easily removed as a unit by merely removing the several screws along the upper flanges of members 12 and 13 and removing the retaining screws, if any, interconnecting end plates 15 and 16. The lower portion of cover 14 is merely slid outwardly to remove the same from the lower flanges of the members 12 and 13. It should be noted that the end plates 15 and 16 retain the lower cover section 14 in position, and prevent longitudinal shifting movement thereof by abutting the end portions thereof.

A conventional elevator conveyor designated by the letter B is best shown in Figs. 1 and 2 and has a relatively small hopper 20 at the bottom thereof, from which the screw conveyor 21 carries the grain upwardly. A discharge outlet 22 is formed on the forward end of the casing 11 surrounding the forward portion of auger 7 for the conveyor extension on the lower side thereof, and discharges the material carried by the auger into the hopper 20. A mounting connection for removably securing the discharge end of the conveyor extension to a conventional elevator conveyor is provided as best shown in Fig. 4. This connector consists in a strap or mounting plate 23 having an upstanding pivot pin 24 fixed thereto. The mounting plate 23 is adapted to be rig-

idly secured to the elevator conveyor as by being rigidly anchored to the side walls of the hopper 28 at the upper portion thereof as by suitable screws and nuts. It will be seen that the pin 24 is not disposed at right angles to the mounting plate of strap 23, but is inclined relative thereto at approximately an angle of 20 degrees less than the normal. Since the maximum angle of the elevator conveyor is approximately 30 degrees, the 10 20 degree angle is approximately an average slope, and will position the pin 24 substantially vertically relative to the ground level to provide a substantially vertical axis on which the extension may be swung. A pair of sleeves 25 and 26 are in the form shown rigidly interconnected and the axes thereof are disposed at right angles, one to the other. The sleeve 25 is adapted to be received on the upstanding pin 24 and a pin 27 is provided to extend through the horizontally disposed sleeve 26. A mounting bracket, such as the substantially U-shaped yoke member 28 as the substantially U-shaped yoke member 28 is provided and is rigidly secured to the forward end 9 of the extension conveyor, as by being welded thereto. The two spaced parallel arms of the yoke 28 are connected respectively at opposite ends of sleeve 26 by the pin 27 and this connection permits swinging movement on a substantially horizontal axis of the conveyor extension to permit optimum positioning thereof. In the form shown, pin 27 consists in a bolt with a head 27a and a nut 27b. Also, it should be noted that there is no means, other than the weight of the conveyor extension, for retaining the sleeve 25 on the pin 24, thus permitting easy removal of the auxiliary conveyor.

The shaft 8 is driven by a drive shaft 29 connected at its upper end to the power source for driving the auger 21, and has a telescoping portion to permit the length to be varied, and permit separation of the two telescoping sections. Any suitable means, such as the polygonal male and female telescoping portions can be provided for producing the driving connection from one end of the shaft 29 to the other. A universal joint 30 is interposed between shaft 29 and the auger shaft 8, and is disposed substantially directly above the pin 24 to facilitate the swinging movement both horizontally and vertically of the conveyor extension. A second universal joint 31 is interposed into the upper portion of shaft 29, and permits the forward end of the extension conveyor to be lifted to remove the sleeve 25 from pin 24, and separate the two sections of the shaft 29 to permit the extension conveyor to be bodily removed from the elevator conveyor B.

With my improved extension conveyor, it is a relatively easy matter to deliver granular products from remote and relatively inaccessible locations to a main elevator conveyor such as the conveyor B. If the grain is to be discharged through a restricted outlet, the hopper A is mounted on the rear portion of the auxiliary conveyor extension, and is positioned below the restricted outlet to receive the grain discharged therethrough. This hopper is of materially greater size than the hopper 20, and is adapted to be positioned in substantially horizontal position with the free end thereof resting on the ground surface to keep the spillage at an absolute minimum. The divider plate 18 of the hopper evenly distributes the grain to the auger 7. The hopper A may be easily removed from the

conveyor extension and the bare conveyor illustrated in Figs. 1 and 5 can be used merely as a drag-out conveyor by merely being positioned within the bin and substantially buried in the grain therein. The extremely simple mounting of the right angle sleeves 25 and 26 on their respective pins 24 and 27 permits the extension to be swung into substantially any desired horizontal position within certain maximum limits.

It will be seen that I have provided an extremely simple, yet highly efficient, connection for interconnecting a conveyor extension and a conventional elevator conveyor, which permits substantially universal positioning of the conveyor extension for optimum efficiency in delivering granular material to the elevator conveyor to facilitate loading thereof.

It should be noted that the ease of removal of the hopper A is an important feature of my conveyor extension, and that by simply removing the side panels 17 from the mounting members 12 and 13, the entire upper portion of the hopper can be bodily removed and the lower casing 14 easily slid off from the mounting members 12 and 13. If the end plate or panel 16 is secured to end plate 10, then, of course, it will be necessary to remove any connections between said plates 10 and 16.

It will of course be understood that various changes may be made in the form, details, arrangements, and proportions of the parts without departing from the scope of my invention.

What I claim is:

1. An auxiliary conveyor extension comprising material transferring means, a driving connection connected with said transferring means and having a universal joint interposed therein, and adapted for connection to a source of rotary driving power, a mounting connection at the discharge end of said material transferring means including a mounting strap adapted for rigid attachment to a suitable mounting structure at the delivery end of said material transferring means, an upstanding pivot pin fixed to said strap and disposed immediately below the intersecting axes of the universal joint of said driving connection, a sleeve journaled on said upstanding pin and pivotally mounted at the delivery end of said transferring means for swinging movement on a horizontal axis.

2. The structure set forth in claim 1 and said vertically disposed sleeve being vertically removable from said upstanding pivot pin, and a second universal joint in said driving connection to facilitate removal of said sleeve from the pin.

HUBERT A. TINTES.
